[57] CLAIM

The ornamental design for a pontoon boat, as shown and described.

DESCRIPTION

FIG. 1 is a perspective view of a pontoon boat showing my new design;

FIG. 2 is a side elevational view thereof; the other side being a mirror image thereof;

FIG. 3 is an top plan view thereof;

FIG. 4 is a front end elevational view thereof;

FIG. 5 is a rear end elevational view thereof; and,

FIG. 6 is a bottom plan view there.

The broken line showing of the guard rail, in FIG. 1, is for illustrative purposes only and forms no part of the claimed design.
